UNITED STATES PATENT OFFICE.

WILLIAM P. BETTENDORF, OF BETTENDORF, IOWA; J. W. BETTENDORF ADMINISTRATOR OF SAID WILLIAM P. BETTENDORF, DECEASED.

MEANS FOR CUSHIONING THE BODIES OF RAILWAY-CARS.

1,091,183.

Specification of Letters Patent.

Patented Mar. 24, 1914.

Application filed May 16, 1910. Serial No. 561,558.

To all whom it may concern:

Be it known that I, WILLIAM P. BETTENDORF, a citizen of the United States, residing at Bettendorf, in the county of Scott and State of Iowa, have invented new and useful Improvements in Means for Cushioning the Bodies of Railway-Cars, of which the following is a full, clear, and exact description.

10 My invention relates to railway cars, and more particularly to tank-cars.

The principal object of my invention is to modify the strain on a railway car when it is subjected to a sudden pull or to a violent buffing contact, and to neutralize the effect of a shifting load, as exemplified by the movement of the liquid contents of a tank car when traveling on a poorly graded or crooked track.

20 A further object of my invention is to flexibly connect the body of said car to the body bolster without affecting the relation of the latter to the underframe of the same. This I accomplish by the means hereinafter 25 fully described and as particularly pointed out in the claims.

In the drawings:—Figure 1 is a side elevation of one end of a tank-car embodying my invention. Fig. 2 is a longitudinal vertical section of the opposite end portion thereof. Fig. 3 is a transverse section through the lower portion of the same, taken in such a plane as to show a side elevation of the bolsters. Fig. 4 is a transverse vertical section through the lower portion of the same, taken on dotted line 4-4. Fig. 1: Fig. 5 is a plan view of the broken away central portion of the body-bolster. Fig. 6 is a horizontal section there- 40 of taken on broken line 6-6, Fig. 2. Fig. 7 is a vertical longitudinal section taken on dotted line 7-7, Fig. 8, drawn to a larger scale and showing parts of the cushioning mechanism in longitudinal section. Fig. 8 is a plan of one end of the under- 45 frame having the tank and other parts removed.

For the purpose of more conveniently explaining my invention, I have confined its 50 application to a tank-car.

In the drawings A represents a suitable tank, that is supported in the transverse plane of the body-bolster by means of saddles B, each consisting of a suitable casting or plate extending transversely between the vertical planes of the car-wheels, and having its upper surface concaved to conform to the curvature of said tank, which is seated therein. At its ends, this saddle is provided with rudimentary feet consisting of downwardly extending hollow boxes, the plane of the under-surface of the ends of which is horizontal. The under-surfaces of these boxes are provided with two or more corresponding corrugations ⁵⁵ that are transverse to the axis of the tank, and rest upon rollers C which latter are of corresponding diameters, and, when the car is stationary will be in a state of rest at the inverted bottom of said corrugations. These rollers are seated in corrugations c, c, in the adjacent ends of cast metal body-bolsters D, the outer ends of which preferably terminate in the same vertical plane as the ends of the saddle, but are provided with integral brackets d that extend in a longitudinally upward direction to and support the running-board E of the car which is riveted thereto and extends from end to end of the car. At its center of length the body-bolster, is provided with a transverse pocket F which extends lengthwise the car in the vertical plane of the king-bolt, Z, and is adapted to contain a coiled spring G placed therein, the ends of which bear against follower-plates f, f, located at each end of said pocket. The ends of the pocket are provided with vertically elongated openings g, and the ends of plungers H, H, extend longitudinally through these openings and engage the follower-plates. The shanks of these plungers enter suitable horizontal sockets, h, made in heads, I, that are made integral with and depend down from the ends of longitudinally extended central portions of the web of saddle j. The ends of plungers H within the heads I, are, preferably, concaved transversely, and impinge against transverse pins J, and said plungers are prevented from having any longi- 95 100

tudinal movement independent of the heads, I, by means of the set-screws k.

The corrugations c, c, of the bolsters, correspond to the corrugations a of the saddle, 5 and when the car is at rest the ridges between these corrugations and the bottoms thereof will be in the same vertical transverse planes. Now when the car is in motion and it is subjected to either a pulling 10 or a buffing strain the momentum of the tank will cause the rollers C, C, to roll up the incline sides of the corrugations and lift the tank, and when this impulse of the tank is spent, its weight will cause the rolls to 15 gravitate to the bottom of the corrugations and return to a state of rest therein. At the same time this action of the rollers C is taking place, the plunger H on the side of the bolster opposite that toward which the tank 20 is moving will, through the medium of the follower f engage and compress spring G, which latter resists and absorbs the shock of the thrust, and when it expands, restores the plungers and the tank to their normal positions. The openings g through which the 25 ends of the plungers H extend in order to engage the followers f, are widened vertically to accommodate the upward movement of the tank, and the saddle due to the action 30 of the rollers C, C. If, however, these rollers C, were dispensed with the opening g would only be of sufficient diameter to permit of the passage of the plungers.

The underside of bolster D, at its center 35 of length, is provided with a male centering plate which is seated in the female centering plate of truck-bolster L, which latter is bellied down at its center of length to enable the center of gravity of the tank to be lowered as much as possible, and the ends of 40 this truck-bolster L are supported by springs resting upon the sill of a suitable bolster opening of the side-frames of the trucks, substantially as shown and described in Letters Patent of the United States granted to me October 6, 1903, No. 740,617.

The rear side of the body-bolster D is provided with wings N the inner vertical surfaces of which are parallel and are arranged substantially equi-distant from the 50 vertical plane of the axis of the tank, and their upper flanges are bent outward and they are otherwise constructed so as to afford means to which the flanges of a horizontally disposed I-beam center-sill M can be secured by means of rivets or otherwise. This horizontally disposed single I-beam center-sill extends longitudinally from the body-bolster at one end of the car, and I 55 prefer to bend the upper flanges of this I-beam center-sill outward, to accommodate and to permit the tank to occupy as low a position as possible and to avoid the shear-

ing strain on the rivets used to secure their ends to wings N.

The front side of the body-bolster is provided with forwardly projecting draft-sill extensions O, O, on each side of the vertical plane of the axis of the tank. These extensions are, preferably, I-shaped in cross section and converge toward each other until they reach a point slightly beyond the transverse vertical plane of the end of the tank car, where they bend upward. From this latter point the draft-sills have their opposing sides parallel to each other, and provided with suitable stop-lugs o for the follower-plates of the draft-rigging (not shown), and have their ends connected by cross-members p' both above and below the drawbar opening. The usual floating end-sills P are mounted transversely upon and carried by these draft-sill extensions o at their outer raised ends, as shown in dotted lines in Fig. 85 of the drawings.

I do not wish to be confined to the cushioning-springs being located in the bolsters, as they can, if desired, be located at the center of length of the car, substantially as shown in a companion application for a modified form of my invention filed May 23, 1910, Serial Number 562,922, but desire to be understood as claiming as my invention the broad idea of both the roller-bearing features, as well as the cushioning of the car-body or tank to limit the extent of the longitudinal movement of the same. If desired these two features can be used in combination or separately.

What I claim as new is:

1. In a railway car, an underframe comprising suitable end-sills, body-bolsters, and a center-sill the ends of which are connected to said body-bolsters, car trucks, a longitudinally arranged cushioning device carried directly by said bolsters, a car-body adapted to have a slight longitudinal movement independent of the underframe, and means connected to and projecting from said car-body adjacent said bolsters that are adapted to engage and compress said cushioning device.

2. In a railway-car, an underframe including body-bolsters and a center-sill supported thereby, centrally disposed seats on said bolsters, suitable cushioning devices retained in said seats, a car-body adapted to have a slight longitudinal movement independent of said underframe, and means connected to and projecting from said car-body adjacent said seats that are adapted to engage and compress said cushioning devices.

3. In a railway car, an underframe having a depressed seat, a car-body adapted to have a slight longitudinal movement independent of said underframe, a suitable lon-

5 longitudinally disposed coil spring retained in said seat, follower-plates at each end thereof, and means connected to and projecting from said car-body and adapted to engage said follower-plates.

4. In a railway car an underframe having a depressed seat, a car-body adapted to have a slight longitudinal movement independent of said underframe, a suitable longitudinally disposed coil-spring retained in said seat, follower-plates at each end thereof, and arms connected to and projecting down from said car-body, and opposing said follower-plates.

15 5. In a railway car, an underframe having a depressed seat, a car-body adapted to have a slight longitudinal movement independent of said underframe, a suitable longitudinally disposed coil-spring retained in said seat, follower-plates at each end thereof, and arms connected to and projecting down from said car-body, plungers secured in said arms in alinement with said spring and extending toward and adapted to engage said followers.

30 6. In a railway car, an underframe comprising a body-bolster having a depressed seat therein, a car-body adapted to have a slight longitudinal movement independent of said underframe, a suitable longitudinally disposed cushioning device, retained in said seat, and arms connected to and projecting down from said car-body, and opposed to the ends of said cushioning device.

35 7. In a railway car, an underframe having a depressed seat, having openings in its ends, a car-body adapted to have a slight longitudinal movement independent of said underframe, a suitable longitudinally disposed cushioning device retained in said seat, arms connected to and projecting down from said car-body, and plungers secured in said arms in alinement with said cushioning device that extend through the openings in the ends of said seat and engage said device.

50 8. In a railway car, an underframe having a depressed seat having vertically widened openings in its ends, a car-body adapted to have simultaneously a slight longitudinal movement and rising and falling movement independent of said underframe, a suitable longitudinally disposed cushioning device retained in said seat, arms connected to and projecting down from said car-body, and plungers secured in said arms in alinement with said cushioning device that extend through the openings in the ends of said seat and engage said device.

60 9. In a railway car, an underframe comprising body-bolsters the center of each of which is provided with a depressed seat having vertically widened openings in its ends,

a car-body adapted to have simultaneously a slight longitudinal movement and rising 65 and falling movement independent of said underframe, a suitable longitudinally disposed cushioning device retained in said seat, arms connected to and projecting down from said car-body, and plungers secured in 70 said arms in alinement with said cushioning device that extend through the openings in the ends of said seat and engage said device.

10 10. In a railway car, an underframe comprising body-bolsters each having a de- 75 pressed seat therein, a single rolled beam center-sill the web connecting the flanged edges of which is disposed horizontally, a car-body adapted to have a slight longitudinal movement independent of said under- 80 frame, and a cushioning device adapted to be retained in said seat and to resist the independent movement of said car-body.

11 11. In a railway car, an underframe comprising body-bolsters each having a de- 85 pressed seat therein, a single rolled beam center-sill, the web connecting the flanged edges of which is disposed horizontally, and the ends of which terminate at and are secured to said bolsters, a car-body adapted to 90 have a slight longitudinal movement independent of said underframe, and a cushioning device adapted to be retained in said seat and to resist the independent movement of said car-body.

95 12. In a railway car, an underframe comprising body-bolsters each having a de- pressed seat therein and having wings projecting from their rear sides, a single rolled beam center-sill the web connecting the 100 flanged edges of which is disposed horizontally and the ends of which terminate between and are secured to said wings, a car- body adapted to have a slight longitudinal movement independent of said underframe, 105 and a cushioning device adapted to be retained in said seat and to resist the independent movement of said car-body.

13. In a railway car, an underframe comprising body-bolsters, each having a de- 110 pressed seat therein, integral draft-sills projecting forward from said bolsters, a car- body adapted to have a slight longitudinal movement independent of said bolsters, and a cushioning device adapted to be retained 115 in said seat and to resist said independent movement of said car-body.

14. In a railway car, an underframe comprising body-bolsters each having a de- 120 pressed seat therein, integral draft-sills projecting forward from said bolsters, a single rolled beam center-sill the web connecting the flanged edges of which is horizontally disposed, a car-body adapted to have a slight longitudinal movement independent 125 of said bolsters, and a cushioning device

- adapted to be retained in said seat and to resist said independent movement of said car-body.
15. In a railway car, an underframe comprising body-bolsters each having a depressed seat therein, integral draft-sills projecting forward from said bolsters, a single rolled beam center-sill the web connecting the flanged edges of which is horizontally disposed, and the ends of which terminate at and are secured to said bolsters, a car-body adapted to have a slight longitudinal movement independent of said bolsters, and a cushioning device adapted to be retained in said seat and to resist said independent movement of said car-body.
16. In a railway car, an underframe comprising body-bolsters each having a depressed seat therein, and having wings projecting from their rear edges, integral draft-sills projecting forward from said bolsters, a single rolled beam center-sill, the web of which is horizontal and the ends connected to and between said wings, a car-body adapted to have a slight longitudinal movement independent of said bolsters, and a cushioning device adapted to be retained in said seat and to resist said independent movement of said car body.
17. In a railway car, the combination with a suitable underframe including bolsters, of a car-body, and separate devices carried by said bolsters that impart a simultaneously and automatically returnable longitudinally reciprocal movement and a rising and falling movement to said car-body independent of said underframe.
18. In a railway car, the combination with a suitable underframe including body-bolsters, of a car-body having a limited longitudinal movement independent of the same, means supported directly by said bolsters adjacent each end of said underframes that are engaged by said car-body and impart a rising and falling movement to it when said car-body moves longitudinally.
19. In a railway car, the combination with a suitable underframe including body-bolsters, of a car-body having a limited longitudinal movement independent of the same, and means carried by said bolster upon which the weight of said car-body rests that automatically actuate the latter to return to its position of rest.
20. A railway car comprising a suitable underframe including body-bolsters, and a car-body having a limited longitudinal movement independent of the underframe, of anti-friction rollers carried directly by said bolsters adjacent each end thereof that are arranged transverse to the length of the car and that directly support the car-body.
21. A railway car comprising a suitable underframe including body bolsters, and a car-body having a limited longitudinal movement independent of the underframe, of anti-friction rollers carried by said bolsters adjacent each end thereof that are arranged transverse to the length of the car and that directly support the car-body, and concave seats therefor in said bolsters.
22. A railway car comprising a suitable underframe, comprising a center-sill and body-bolsters, corrugated roller-bearing seats arranged transverse to the length of the car and supported by said body bolsters, a car-body having a limited longitudinal movement independent of said underframe, and inverted corrugated roller seats secured to said car-body and arranged parallel to those first mentioned, and rollers placed between said seats and devices for returning said car to normal position after being moved independent of said underframe.
23. A railway car comprising a suitable underframe, which includes a longitudinal center-sill and body-bolsters, and a car-body having a longitudinal movement independent of said underframe, of means supported by said underframe adjacent each end thereof, that directly supports said car-body and are interposed between the same and said underframe, and longitudinally disposed cushioning devices adjacent said body bolsters for limiting the movement of said car-body on said underframe and which return said car-body to normal after each longitudinal movement of the latter.
24. A railway car comprising a suitable underframe which includes a longitudinal center-sill and body-bolsters, and a car-body having a longitudinal movement independent of said underframe, of means supported by said underframe adjacent each end thereof that directly supports said car-body and are interposed between the same and said underframe, and longitudinally disposed cushioning devices disposed on each side of said body-bolsters for limiting the movement of said car-body on said underframe and which return said car-body to normal after each longitudinal movement of the latter.
25. A railway car comprising a suitable underframe having a center-sill and body-bolsters, and a car-body having a longitudinal movement independent of said underframe, of anti-friction rollers arranged transverse to the length of the car and located adjacent the ends thereof that are interposed between said underframe and said car-body and directly support the latter, and devices for limiting the longitudinal movement of the car body.
26. A railway car comprising a suitable underframe having a center-sill and body-

bolsters, corrugated roller-bearing seats supported thereby adjacent the ends of the car and arranged transversely to the length of the same, a car-body having a longitudinal movement independent of said under-frame, inverted corrugated roller-seats secured to and similarly arranged upon said car-body, of longitudinally disposed cushioning devices for limiting the movement of said car-
10 body and which return said car-body to normal after each longitudinal movement of the latter, and rollers placed between said seats.

27. In a railway car, an underframe having a depressed seat, a car-body adapted to have a slight longitudinal movement independent of said underframe, roller bearing interposed between said underframe and car-body and supporting the latter, a suitable longitudinally disposed coil spring retained in said seat, follower-plates at each end thereof, and means connected to and projecting from said car-body and adapted to engage said follower-plates.

25 28. In a railway car an underframe having a depressed seat, a car-body adapted to have a slight longitudinal movement independent of said underframe, roller bearings interposed between said underframe and car-body and supporting the latter, a suitable longitudinally disposed coil-spring retained in said seat, follower-plates at each end thereof, and arms connected to and projecting down from said car-body, and opposing said follower-plates.

29. In a railway car, an underframe having a depressed seat, a car-body adapted to have a slight longitudinal movement independent of said underframe, roller bearings interposed between said underframe and car-body and supporting the latter, a suitable longitudinally disposed coil-spring retained in said seat, follower-plates at each end thereof, and arms connected to and projecting down from said car-body, plungers secured in said arms in alinement with said spring and extending toward and adapted to engage said followers.

30. In a railway car, an underframe having a depressed seat having vertically widened openings in its ends, a car-body adapted to have simultaneously a slight longitudinal movement and rising and falling movement independent of said underframe, roller bearings interposed between said underframe and car-body and supporting the latter, a suitable longitudinally disposed cushioning device retained in said seat, arms connected to and projecting down from said car-body, and plungers secured in said arms in alinement with said cushioning device that extend through the openings in the ends of said seat and engage said device.

31. In a railway car, an underframe comprising body-bolsters each having a depressed seat therein, a single rolled beam center-sill the web connecting the flanged edges of which is disposed horizontally, a car-body adapted to have a slight longitudinal movement independent of said under-frame, roller bearings interposed between said underframe and car-body and supporting the latter, and a cushioning device adapted to be retained in said seat and to resist the independent movement of said car-
70 body.

32. In a railway car, an underframe comprising body-bolsters each having a depressed seat therein, a single rolled beam center-sill, the web connecting the flanged edges of which is disposed horizontally, and the ends of which terminate at and are secured to said bolsters, a car-body adapted to have a slight longitudinal movement independent of said underframe, roller bearings interposed between said underframe and car-body and supporting the latter, and a cushioning device adapted to be retained in said seat and to resist the independent movement of said car-body.

33. A car structure including a car body; a supporting structure upon which the car body may move longitudinally with respect to the supporting structure; and buffer mechanism for yieldingly limiting movement of the car body longitudinally of the supporting structure, said buffer mechanism including a follower device, an abutment therefor, spring mechanism, means whereby the spring mechanism presses the follower device against its abutment when the car body moves in one direction and for causing the follower device to move from its abutment and to be pressed upon the spring mechanism when the car body is moved in the reverse direction and a second abutment against which the spring mechanism is pressed when the car body is moved in the latter direction.

34. A car structure including a car body; a supporting structure therefor upon which the car body may move longitudinally with respect to the supporting structure; buffer mechanism for yieldingly limiting movement of the car body longitudinally of the supporting structure, said buffer mechanism including abutments, spring mechanism interposed between the abutments, said spring mechanism being in separable relation with each abutment, and means whereby the car body in moving in one direction with respect to its supporting structure will cause the spring mechanism to leave one of its abutments and be pressed against its other abutment and whereby when the car body is moved in the reverse direction with re-

spect to its supporting structure it will leave the last mentioned abutment and be pressed against the abutment companion thereto.

5 35. A car structure including a car body; a supporting structure therefor upon which the car body may move longitudinally with respect to the supporting structure; buffer mechanism for yieldingly limiting movement of the car body longitudinally of the supporting structure, said buffer mechanism including abutments, spring mechanism in-

terposed between the abutments, and means whereby the car body in moving in one direction with respect to its supporting structure will cause the spring mechanism to leave one of its abutments and be pressed against its other abutment. 15

In witness whereof I have hereunto set my hand this 12th day of May 1910.

WILLIAM P. BETTENDORF.
